METHOD FOR WINDING

Philip R. Hirsh, Montclair, N. J., assignor to Lock Joint Pipe Company, East Orange, N. J., a corporation of New Jersey

Application October 15, 1945, Serial No. 622,343

4 Claims. (Cl. 242—11)

1

This invention relates to a method for winding a line about a core, and more particularly to wrapping a core, such as a pipe or other object, with a tensioned wire wrapping extending from end to end of the core.

Among the objects of the present invention is to provide an improved process for wrapping a core with a tensioned wire by a single pass of wire alongside a rotating core and in which the wire being wrapped about the core is tensioned through a sheave from which the wire extends to opposite sides of the core. In the United States Patent No. 2,348,765, a core-winding process is described wherein the end of a wire is attached to one end of the core and the wire is helically wound around the core to form a temporary wrapping. For applying a permanent wrapping, the wire at the terminus of the temporary wrapping is passed over a sheave and is then brought back to the core and attached thereto adjacent the last wrap of the temporary wrapping. Tension is applied to the two leads of wire extending to the core and the sheave, and the core is then rotated in such direction as to unwind the temporary wrapping as the sheave is translated towards the initial end of the temporary wrapping. As the core is rotated and the sheave is translated the wire leaving the temporary wrapping is reapplied to the core as a permanent wrapping under tension. When the sheave has returned to its initial position, the end of the permanent wrapping is secured to the core and the wire is cut beyond the place of securing. The described process has the advantage of providing balanced couples upon the core as the result of equal and opposite forces transmitted through the two tensioned leads of wire extending between the sheave and the core so that the power required to rotate the core in applying the permanent wrapping is only slightly more than would be necessary to rotate the core idly. The process is also suitable for applying a highly tensioned wrapping having a known and constant tension throughout the length of the wrapping. The present invention has as an object the retention of these advantages by providing a process whereby only one pass of a tension-applying sheave lengthwise of the core is employed for applying a tensioned wrapping.

A further object of the present invention is to enable concluding a tensioned wrapping as close to the ends of a core as desired with only one pass of a tensioning device lengthwise of the core.

Other objects and advantages of the present invention will be hereinafter set forth in the accompanying specification and claims, and illus-

2

trated in the drawings in which sequential stages in the process of wrapping a wire about a core are shown.

Figure 1 illustrates the right end of a core to which a cinch winding or snubbing has been applied;

Fig. 2 illustrates the application of a weighted sheave to a loop of wire between the anchored end of the wire and the cinch winding;

Fig. 3 illustrates an intermediate stage of the wrapping of the core as it progresses from the right end to the left end of the core;

Fig. 4 illustrates the stage at which the wound wrapping has reached the left end of the core and has been fastened to the core;

Fig. 5 is a section at line 5—5 of Fig. 2;

Fig. 6 is a longitudinal section through a portion of the left end of a core and an attached mandrel or other device which provides a surface in continuation of the surface of the core,

The machine for winding a core, pipe, or other object is provided with rollers for rotatively supporting the core. The core is rotated during a wire-winding operation. The process of the present invention may be practiced with any of the machines described in the United States Patent No. 2,348,765, and, therefore, schematic illustrations of the manner in which the process is performed will suffice to provide a thorough understanding and disclosure of the invention.

Referring to the drawings, the length of the core 10 is extended at one end by a mandrel 11 or other form of device capable of providing a surface continuing beyond the end of the core, as shown in Figs. 4 and 6. The combined core and mandrel is mounted as a unit in the machine by which it is supported on two pairs of rollers 12 and 13, one at each end of the unit. A runner ring 14, which is temporarily fastened to one end of the core, rests upon one pair of rollers 12, and the other end of the unit is supported by the other pair of rollers 13, which engage a flange 15 of the mandrel.

The winding machine is provided with a travelling carriage (not shown) which moves alongside of the core and carries a guide 16 for the feed portion of the wire which passes to the core. The wire passes freely through the guide and is laid onto the core in a helical course 17, Fig. 1. Sheave 18, by which the wire to be permanently applied is tensioned, travels lengthwise of the core at the rate of travel of guide 16 and may be guided by the travelling carriage or left to be controlled by the pitch of the wire wrapping 17 previously wound onto the core. As shown in Fig.

2, the sheave is engaged by a loop 19 of the wire between turns 17 and the end of the wire which is permanently anchored to the core at 20. The wire of the permanent winding starts at 20, Fig. 2, and tensioned by the application of force to the sheave. In the drawings I have illustrated the sheave as being weighted and suspended from the loop 19, Figs. 2, 3, 4 and 5, but other force-applying means, such as described in the aforesaid patent, may be employed for applying the desired tension.

The core 16, which may be a pipe or solid body in any form, is shown as a steel sleeve 21 with a bell ring 22 fastened thereto. The mandrel 11 may be made up of a plurality of plain rings 15, 23, 24, 25 and 26, as illustrated in Fig. 6, which are joined together to constitute a single device detachably connected to the core. The mandrel preferably is designed frictionally to engage with the interior of the core. In assembling the mandrel onto the end of the core, it is then necessary only that the mandrel be shoved home into snug fitting relationship with the bell ring. The assembled core and mandrel are mounted as a unit in the winding machine.

After the core and its attached mandrel are mounted in the machine, the end of wire is temporarily attached to one end of the core, as at 27, Fig. 1, and the core is rotated sufficiently to apply a few turns 17 of the wire about the core. These turns of wire are applied without tension or with only such tension as is afforded by slight drag on the reel from which the wire is drawn or on the wire itself.

The end of the wire which is temporarily attached to the core at 27 is then detached therefrom and unwound from the core sufficiently to form a loop 19 for engaging the tensioning sheave 18. This end of the wire is looped about the sheave and fastened to the core, as at 20, Fig. 2. Any kind of an anchoring device which will serve to permanently secure the end of the wire to the core may be used. The wire in the loop of wire engaged by the sheave is subjected to tensile stress by the application of a predetermined load 28 on the sheave. The turns of wire which are located between guide 16 and sheave 18 provide sufficient snubbing effect to prevent slippage of the wire under the tension exerted by the applied load.

The wire winding machine is then operated, and starting from the anchored end 20, the wire is helically wrapped about the core as a permanent wrapping 29 as guide 16 is moved toward the other end of the core and the core is rotated clockwise as viewed in Fig. 5. The wire passing through guide 16 winds into and unwinds from the cinch turns 17, passes over sheave 18, and enters the permanent winding 29.

An intermediate position of the tensioning sheave and guide is illustrated in Fig. 3. At this position the winding being permanently applied is to the right of the sheave 18, and the cinch winding is to the left of the sheave. As the operation of the machine continues, the permanent winding is extended towards the left end of the core with the cinch turns preceding it.

When the tensioning sheave comes to a selected position opposite the end of the core, the operation of the machine is discontinued. In this position, the cinch turns have advanced over the mandrel as illustrated in Fig. 4. The end of the permanent winding may then be anchored to the core as close to the end of the core as is desired.

For anchoring purposes, any suitable anchoring device may be used. If a sleeve of the type illustrated in United States Patent No. 2,375,921 is preferred, it is necessary to initially thread the wire through the sleeve at the beginning of the wire-winding operation. Such a sleeve 30 is illustrated in Figs. 1, 2 and 3 as being slidably mounted upon the wire and held in a reserve position by guide 16. The sleeve is held by this guide as the wire loosely passes therethrough and until the wire winding operation nears completion. It is then released from the guide member and secured to the wire. The latter operation occurs at such a place as to locate the sleeve against the core where it is desired it be fastened to the core as shown in Fig. 4. An experienced operator soon determines at what stage of the winding operation it is necessary to stop the machine and fasten the sleeve to the wire in order to locate it in the position desired against the core. The sleeve is then welded to or otherwise attached to the core.

After the wire is thus securely anchored and after the weight has been relieved from the sheave, the wire is cut beyond the anchor, that is to say, between the anchor 30 and the cinch turns 17, as at 31, Fig. 4. The process just described completes the wire winding of the core, and it remains only to unwind the cinch turns and dismount the core and attached mandrel. The mandrel is then removed from the core.

If preferred, instead of using a detachable mandrel as an extension of the core for receiving the cinch turns, the cinch turns may be made to run upon the surface of a chuck or other rotating part of the winding machine which closely fits with the core and provides a surface in continuation of the surface of the core being wrapped.

What is claimed is:

1. In a method for wrapping a line about a core, the steps comprising applying a mandrel to one end of a core, attaching the end of a line to the other end of the core, snubbing the line on the core adjacent the attached end by applying turns of line about the core in sufficient number to prevent slippage of the line when tensioned and leaving a loop of line between the snubbing and the attached end, tensioning the line between the snubbing and attached end by applying force to the loop of line, winding a permanent winding onto the core by rotating the core while translating the loop of line longitudinally of the core and continuing the application of the permanent winding until the snubbing has passed onto the mandrel, securing the permanent winding to the core, relieving the applied force, and severing the snubbing from the last secured end of the line.

2. In a method for wrapping a line around a core, the steps comprising snubbing a length of line about a core, attaching the end of the line to the core with a loop between the snubbing and the attached end, applying force to the loop in the line, applying a permanent winding to the core starting from the point of attachment by rotating the core and translating the formed loop and snubbing longitudinally of the core, continuing the application of the permanent winding until it has reached the other end of the core and the snubbing has passed beyond the core and onto a receiving surface, attaching the wound line to the core, releasing the force on the loop of line, and severing the snubbing from the permanent winding remaining on the core.

3. In a method for wrapping a line about a core, the steps comprising attaching to one end of a core a mandrel having a surface in continuation of the core, feeding a line to provide cinch turns about the core in sufficient number to prevent slippage of the line when the line is subsequently stressed, securing the free end of the line to the core, stressing the line between said cinch turns and the portion of the line which is secured to the core, applying a line about the core by relatively rotating and translating the core and the cinch turns and thereby winding and unwinding the cinch turns and winding the line therefrom and into a permanent wrapping about the core, extending the permanent wrapping in such fashion and until the cinch turns have passed onto the surface of the mandrel attached to the core, and then securing the permanent wrapping to the core.

4. In a method for wrapping a line about a core, the steps comprising applying cinch turns of line about a core in sufficient number to prevent slippage of the line when subsequently stressed, securing the free end of the line to the core, stressing the line between the secured end

5 and the cinch turns, unwinding the cinch turns and winding the line therefrom into a permanent wrapping of tensioned line about the core as line is run into the cinch turns and the length of the permanent wrapping is increased, continuing the winding of the permanent wrapping as the cinch turns reach and extend onto a receiving surface beyond the end of the core, and securing to the core a portion of the line intermediate the permanent wrapping and the cinch turns.
